INVENTOR

WILFORD H. PIKE

BY

Harry S. Schwoeber
ATTORNEY

UNITED STATES PATENT OFFICE.

WILFORD H. PIKE, OF OAKLAND, CALIFORNIA.

HAT HOLDER.

Application filed April 16, 1923. Serial No. 632,209.

To all whom it may concern:

Be it known that I, WILFORD H. PIKE, a citizen of the United States, residing at Oakland, in the county of Alameda and State of California, have invented certain new and useful Improvements in Hat Holders, of which the following is a specification.

My invention is an improved hat rack for automobiles.

10 The object of my invention is to provide a simple and efficient means for securely holding a hat in an automobile.

Another object of my invention is to provide a hat rack which is simple in construction and inexpensive to manufacture.

Referring to the drawing which forms a part of this specification—

Figure 1. is a side view of my hat rack attached to an automobile top.

20 Figure 2. is a top plan view of the holding frame.

Figure 3. is a plan view of the adjusting link.

25 Figure 4. is a front view of the fastening plate.

Figure 5. is a top plan view of the same.

Figure 6. is a side view of a modified form of attaching my rack.

Referring more particularly to the drawing:—the numeral 1 indicates an L-shaped fastening plate. This plate is fastened to the automobile top bow by suitable screws 2 which pass thru the plate leg 3. The leg 3 may be placed either on top or on the bottom of the bow as shown in Figures 1 and 6.

Flanges 4 project from the leg 5 of the fastening plate. A holding frame 6 is pivoted to the flanges 4. The holding frame 6

is formed of a single piece of wire, comprising a hat holding ring 7, preferably substantially elliptical in shape and a pair of substantially horizontal arms 8 which have outwardly projecting ends 9 that extend into the flanges 4 thereby pivoting said holding frame to the fastening plate 1. On the lower edge of the arms 8 are formed a plurality of notches 10 which are adapted to receive a U-shaped adjusting link 11. The link 11 is pivoted to the flanges 4 by lugs 12. As the link 11 is moved rearwardly the hat holding ring 7 drops away from the automobile top the desired distance to accommodate various hats.

Having described my invention I claim:—

1. A hat rack comprising a fastening plate, flanges on said plate, a holding frame pivoted to said flanges, said holding frame comprising a hat ring, arms connecting said ring to said flanges and provided with a plurality of notches, an adjusting link pivoted to said flanges and adapted to project into any one of the said notches whereby the ring might be held in any one of a plurality of positions.

2. A hat rack comprising a fastening plate, flanges on said plate, a holding frame pivoted to said flanges, said holding frame comprising a hat ring and rearwardly extending horizontal arms, an adjusting link pivoted to said flanges, said holding frame arms having a plurality of notches formed therein, for the reception of said adjusting link.

In testimony whereof I affix my signature.

WILFORD H. PIKE.
